UNITED STATES PATENT OFFICE.

WILLIAM D. McCOY, OF BROOKLYN, NEW YORK, ASSIGNOR TO MCCOY COTTON MACHINERY CORPORATION, A CORPORATION OF NEW YORK.

GINNING AND CLEANING MACHINE.

Application filed December 29, 1915, Serial No. 69,142. Renewed March 22, 1921. Serial No. 454,417.

To all whom it may concern:

Be it known that I, WILLIAM D. McCOY, a citizen of the United States of America, residing at Brooklyn, N. Y., have invented a new and useful Ginning and Cleaning Machine, of which the following is a specification.

My invention relates to the ginning of material such as cotton and the general objects 10 of my invention are to produce a machine of simple, compact and inexpensive construction for the ginning of cotton and similar materials which will operate rapidly and effectively and which will gin the short and 15 the long staple cotton without injuring the fibres and without breaking the seeds.

Other objects are to avoid waste of lint through incomplete ginning and to secure a finished product which will sample to the 20 highest possible grade.

In the accomplishment of the foregoing and other objects I employ a grid or ginning wall made up of closely spaced, relatively small rods and a wiper of frictional material 25 held in yielding engagement with said grid, relative motion being imparted to the grid and wiper in a direction transverse to the rods of the grid so as to cause the fibres protruding through the grid to be caught and 30 pulled through by the wiper. According to the preferred construction the grid, or ginning wall, is in the form of a cylinder and a plurality of the wipers engage with the inner surface of this ginning wall.

The fibres are preferably started through 35 the interstices in the ginning wall by a current of induced air and this same flow of air is usually relied upon to carry off the lint to a bin or other receptacle.

Various other features and details of construction will appear as the specification proceeds, attention being directed to the accompanying drawings illustrating the invention embodied in a practical and preferred form.

In these drawings:

Fig. 1, is a view partly in vertical section and partly in side elevation of the machine constructed in accordance with and embody-

ing the invention, the section being taken 50 substantially on the plane of the line 1—1 of Fig. 3.

Fig. 2, is a perspective view of the ginning cylinder illustrating its method of construction.

Fig. 3, is a part sectional view taken at the left hand end of the machine illustrated in Fig. 1.

Fig. 4, is a fragmentary sectional view taken at the opposite side of the hopper in Fig. 1.

Fig. 5, is a detail detached view of one of the wiper pads and its spring support.

In the machine herein illustrated, both the ginning cylinder and the wiper blades are 65 mounted on a single supporting shaft 7 which serves both as a support and as a means for rotating one of these members in respect to the other member.

The construction of the grid or ginning 70 cylinder will be best understood by reference to Fig. 2 wherein the same is shown as made up of a hub 9 supporting radiating arms 10 which carry a ring 11, this ring having secured therein a plurality of closely spaced 75 relatively small round rods 12. These rods, it will be clear, provide between them a plurality of interstices or ginning openings 13 having, on account of the rounded shape of the rods, tapering inlets on one side and 80 flaring outlets on the other side, this shape facilitating passage of the fibres and air therethrough. A second ring 14 is preferably engaged with the ends of the grid bars or rods 12 thus constituting the whole an 85 opened ended cylinder supported on the shaft 7 by the hub 9 at one end thereof.

The wipers consist in the present embodiment of pads, blocks or strips 15 of rubber composition or other somewhat resilient material possessing the necessary frictional qualities, carried by spring arms 16 secured to a hub 17 supported on the end of the shaft 7 and projecting within the open end of the ginning cylinder.

The spring supporting arms 16 illustrated are of novel construction consisting of two plates of spring metal, the upper one having

a tongue 18 engaging in a groove 19 in one edge of the wiper pad and the lower one extending across the back of the pad as shown at 20 and having an inturned tongue 21 at 6 the end thereof engaging in a groove 22 in the opposite edge of the pad. These two spring plates have a tendency to separate or bow apart and it will be evident that by drawing the intermediate portions of the 10 plates together as by means of the securing screws 23, the gripping end portions of said plates will be forced into gripping engagement with the slots in the pads.

The seed cotton or other material to be 15 ginned is supplied to and supported by the outer surface of the ginning cylinder and for confining it in such relation I have provided a casing which may be in the form of a hopper consisting in the present disclosure, of 20 two side plates 25 and 26 connected at their outer peripheries by an outer reticulated wall 27, said side plates surrounding the ginning cylinder and bearing on the annular shoulders or tracks 25' and 26' formed on the rings 11 25 and 14 at the opposite sides of the ginning surface. This hopper is provided with a supply chute 28 in which the seed cotton or other material is inserted.

The annular supply hopper is held against 30 rotation by means consisting in the present disclosure of a rod 30 carried by the side plates and extending into slots 31 in the supporting brackets 32 and 33. Springs 34 are illustrated exerting their tension to 35 hold the positioning rod 30 at one end of said slots.

The hopper holding means just described 40 is utilized in the present illustration as a part of the means for oscillating or vibrating the hopper for the purpose of agitating the contents thereof, this being accomplished by providing a cam 35 on the ginning cylinder, which by engagement with the outstanding spring arms 36 on the outer side 45 plate 25, tends to impart a momentary forward rotation to the hopper against the tension of the springs 34. The engagement of this cam therefore with these spring fingers 36 tends to vibrate the hopper and thus agitates the contents freeing the ginned seed 50 from the unginned and permitting the same to fall through the openings in the reticulated wall.

From the foregoing it will be apparent 55 that when a supply of seed cotton or the like is placed in the hopper, said material will be sucked against and be supported by the outer surface of the ginning cylinder and that upon relative rotation between said ginning cylinder and the wipers being set up the fibres projecting through the interstices in the cylinder will be caught by the wipers and be drawn through into the cylinder. The machine illustrated is designed to permit of the rotation of either the grid or the

wipers. As shown in Fig. 1 the grid is the relatively rotating member and the wipers remain relatively stationary. This is accomplished in the illustration by keying the grid supporting hub to the shaft by means of a set screw 38 and by holding the wiper supporting hub against rotation by means of a hollow locking pin 39 passed through an opening 40 in the casing 41 into engagement over a set screw 42 on said hub. The wiper hub is thus in this case held against rotation while the grid rotates with the shaft. The reverse arrangement can be effected by removing the locking pin 39 and tightening the set screw 42, loosening the set screw 38 which fastened the grid to the shaft and by turning in the bolt 43 into engagement with a seat 44 in one of the radial arms of the grid supporting hub. The grid is now in this instance held relatively stationary while the wipers rotate with the shaft.

The ginning action of the wipers is facilitated by the circulation of a current of air or other medium from the outer or supporting surface of the ginning wall through the interstices therein. This current flow towards the wipers partially separates the fibres and carries them through the interstices in the grid into range of the wipers and the wipers engaging and rubbing over the round surfaces presented by the grid rods draw out the fibres without injuring or breaking the same and wholly separate the fibres from the seeds. The current of air is provided for in the present disclosure by having a suction conduit 45 connected to the casing 41 which confronts the open inner end of the ginning cylinder, the spaces between the arms of the supporting hub 9 at the outer end of the cylinder being closed by a plate 46 which may be made transparent for the purpose of observing the action within the ginning cylinder, said plate having an opening or openings 47 to receive the locking screw 43 when the same is used.

A baffle may be provided for intercepting the material carried by the outer surface of the ginning cylinder, such a baffle being illustrated as made up of a series of downwardly bent fingers 53 overlying the outer surface of the cylinder and carried by a shaft 54 which is adapted to be periodically tripped by the engagement of the cam 35 with a tripper arm 55 on the end of said shaft. This shaft is normally held with the baffle fingers in the depressed position with the ends of the fingers close to the grid rods by means of a spring 56 connected to an arm 57 on one end of the shaft and anchored to a pin 58 on the side plate 26, the downward movement of the baffle fingers being limited by the engagement of the arm 57 with a stop lug 59.

The vibrations imparted to the casing or hopper impart vibrations to the baffles which

are carried by the casing and thus induce a peculiarly advantageous action of the baffles on the seed, which action is quite independent of the lifting of the baffles by means of 5 the members 35 and 55.

The seeds and foreign matter may be carried off by suitable means such as the screw conveyor illustrated at 60 in Fig. 1 working in a trough 61 disposed beneath the reticulated wall of the hopper so as to receive the 10 seeds, etc., therefrom.

The baffle fingers are preferably yielding in character, as by making them of spring wire, so as to yield under the impact of the 15 seeds and so prevent breaking or injuring the seeds. These baffles also are preferably located in the plane of a wiper at the opposite side of the grid so as to act upon the seeds at one side of the grid while the fibres 20 of the seeds are being acted upon at the opposite side of the grid. The result of this is that the seeds are shifted sideways or longitudinally of the grid rods by their engagement with the inclined baffle fingers and 25 the fibres being held at this time by the wipers, a more effective separation of the fibres from the seed is effected.

The current of inflowing air passing through the grid clears the wipers of the 30 fibres which they have separated from the seeds, the air thus performing the double function of introducing the fibres in through the interstices in the grid and then carrying off the ginned cotton laterally 35 away from the ginning mechanism. This conducting or carrying off effect is enhanced by admitting a certain amount of free air at the outer end of the ginning cylinder. Thus in the machine illustrated air is admitted 40 at the outer end of the cylinder through a plurality of openings 47. These currents of air constitute carrying currents for floating off the ginned cotton and flowing longitudinally of the wiper pads they 45 serve to draw the fibres off the ends of the wiper pads as fast as separation from the seed is accomplished. The circulating air currents therefore serve to keep the wipers free of loose fibres and prevent any accumulation 50 thereof. The air has the further effect of keeping the parts cool, this cooling function being facilitated by reason of the relatively small size of the rods and wipers.

The annular hopper which surrounds the 55 ginning cylinder confines the material to the extent of preventing the escape of the incompletely ginned seed, the agitation imparted to said hopper shaking up the un-ginned seed so as to cause the same to be 60 caught by the inflowing air currents and carried into engagement with the ginning cylinder. This agitation also prevents matting of the material. The openings in the reticulated wall 27 are of a size to just pass 65 the completely ginned seeds.

Attention is also directed to the advantage of mounting the wiper pads on yielding spring arms, these arms taking up the wear of the pads and serving to always preserve a proper engagement of the pads with the 70 grid.

Another important feature of my invention is that in the relative movement of the ginning cylinder and wipers the fibres will be engaged by successive wipers, an easy 75 and gradual separation being thereby accomplished without breaking or injuring the fibres.

What I claim is:—

1. In apparatus of the character set forth, 80 a ginning wall composed of closely spaced, relatively small, rounded rods forming a grid adapted to support a body of seed cotton or the like material, a plurality of wipers yieldingly engaging the side of the 85 grid opposite the side which supports the body of material to be ginned and means for imparting relative motion to said wipers and ginning wall transversely to the rods composing the ginning wall whereby said 90 wipers will frictionally engage the fibres projecting through the interstices between the rods and draw said fibres through said ginning wall.

2. In apparatus of the character set forth, 95 a ginning wall composed of closely spaced relatively small, rounded rods forming a grid adapted to support a body of seed cotton or the like material, a plurality of wipers yieldingly engaging the side of the 100 grid opposite the side which supports the body of material to be ginned, means for imparting relative motion to said wipers and ginning wall transversely to the rods composing the ginning wall whereby said 105 wipers will frictionally engage the fibres projecting through the interstices between the rods and draw said fibres through said ginning wall and means for circulating a fluid through the grid from the supporting 110 side thereof toward the side where the wipers are located whereby to carry the fibres through the ginning wall into the grasp of the wipers.

3. In apparatus of the character de- 115 scribed, a substantially circular ginning wall composed of closely spaced relatively small rods, means for confining a body of seed cotton or the like material on the outer surface of said circular grid, wipers yield- 120 ingly engaging the inner surface of said circular grid and means for producing relative rotation between said wipers and circular grid.

4. In apparatus of the character de- 125 scribed, a substantially circular ginning wall composed of closely spaced relatively small rods, means for confining a body of seed cotton or the like material on the outer surface of said circular grid, wipers yield- 130

ingly engaging the inner surface of said circular grid, means for producing relative rotation between said wipers and circular grid and means for inducing a current flow from the outside of said grid through the circular grid to the wipers within the same.

5. In apparatus of the character described, a substantially circular ginning wall 10 composed of closely spaced relatively small rods, means for confining a body of seed cotton or the like material on the outer surface of said circular grid, wipers yieldingly engaging the inner surface of said 15 circular grid, means for maintaining the circular grid relatively stationary and means for rotating the wipers within the grid.

6. In apparatus of the character described, a substantially circular ginning wall 20 composed of closely spaced relatively small rods, means for confining a body of seed cotton or the like material on the one surface of said circular grid, wipers yieldingly engaging the opposite surface of said 25 circular grid, means for maintaining the wipers relatively stationary and means for rotating the grid with respect to said wipers.

7. In apparatus of the character described, a substantially circular ginning wall 30 composed of closely spaced relatively small rods, means for confining a body of seed cotton or the like material on the one surface of said circular grid, wipers yieldingly engaging the opposite surface of said 35 circular grid, means for producing relative rotation between said wipers and circular grid, a baffle disposed in operative 40 relation to said circular grid and means for intermittently lifting said baffle.

8. In apparatus of the character described, a substantially circular ginning wall 45 composed of closely spaced relatively small rods, means for confining a body of seed cotton or the like material on the one surface of said circular grid, wipers yieldingly engaging the opposite surface of said 50 circular grid, means for producing relative rotation between said wipers and circular grid and means for agitating the material supported on the grid.

9. In apparatus of the character set forth, a ginning wall composed of substantially 55 parallel rounded rods in closely spaced relation forming a grid having relatively narrow interstices with rounded tapering entrances and rounded flaring exits, means for supplying seed cotton or the like to one side 60 of said ginning wall, a wiper yieldingly engaging the opposite side of said ginning wall, means for inducing a current flow through said grid from the side where the seed cotton is supplied to the opposite side 65 where the wiper is located and means for

imparting relative motion to said wiper and ginning wall, whereby fibres on the supply side of said ginning wall will be drawn by the current flow through the interstices therein and be engaged and pulled there-through by the wiper at the opposite side of said wall.

10. In apparatus of the character set forth, a ginning cylinder having interstices 70 in the periphery thereof, forming said peripheral portions into a ginning wall and supporting tracks at opposite sides of said ginning wall, side plates bearing on said supporting tracks, an outer wall connecting said side plates and forming in conjunction therewith a cylindrical hopper surrounding the ginning cylinder and wipers yieldingly engaging the inner surface of the ginning wall.

11. In an apparatus of the character set forth, the combination with a grip composed 85 of closely spaced bars having rounded portions forming throats at one side of the grid to receive fibre and air, and rounded portions forming discharge exits at the opposite side of the grid for the same, of wipers disposed in spaced relation and bearing on the exit side of the grid, means for producing relative motion between the wipers and grid and means for creating a flow of air from the opposite side of the grid through the rounded throats to the exit side of the grid, whereby fibres at said first side of the grid will be carried through the rounded throats to the exit side of the grid 90 and be there engaged by the wipers and drawn into the space between said wipers.

12. In apparatus of the character set forth, a ginning cylinder comprising a supporting hub, arms radiating therefrom, a ring supported by said arms, a second ring, closely spaced relatively small rods connecting said rings and forming a substantially cylindrical ginning wall, wipers yieldingly 100 engaging the surface of said ginning wall, a shaft on which the hub of the ginning cylinder is mounted, a hub supporting the wipers and also engaged on said shaft, means for securing one of said hubs to said shaft to cause the same to rotate therewith and means for holding the other of said hubs relatively stationary.

13. In an apparatus of the character set forth, a supporting shaft, a ginning cylinder having a supporting hub at one end thereof 110 engaged on said shaft, a relatively transparent plate closing said hub end of the ginning cylinder, a hub entered into the opposite open end of the ginning cylinder and yielding wipers carried by said second hub 115 engaging the inner wall of the ginning cylinder.

14. In an apparatus of the character set forth, a supporting shaft, a ginning cylinder having a supporting hub at one end 120

- thereof engaged on said shaft, a second hub mounted on said shaft at the opposite open end of said ginning cylinder, wipers carried by said second hub yieldingly engaging the inner wall of the ginning cylinder, means for securing one of said hubs to said shaft to cause the same to rotate therewith and means for securing the other of said hubs against rotation.
- 10 15. In an apparatus of the character set forth, a ginning cylinder, blocks of resilient frictional material bearing on the surface of said ginning cylinder, spring members supporting said resilient frictional blocks in yielding engagement with the ginning cylinder and means for imparting relative rotation to said ginning cylinder and friction blocks.
- 15 16. In apparatus of the character set forth, a ginning wall, pads of resilient frictional material engaging the surface of said ginning wall, spring members holding said pads in yielding engagement with said ginning wall and means for imparting relative movement to said ginning wall and spring pressed pads.
- 20 17. In apparatus of the character set forth, a ginning cylinder having interstices in the periphery thereof forming said peripheral portions into a ginning wall and supporting tracks at opposite sides of said ginning wall, side plates bearing on said supporting tracks, an outer wall connecting said side plates and forming in conjunction therewith a cylindrical hopper surrounding the ginning cylinder, wipers yieldingly engaging the inner surface of the ginning wall, and means for imparting an oscillatory movement of said hopper in agitating the contents thereof.
- 25 18. In apparatus of the character described, a grid member having cotton fiber passages therethrough smaller than the cotton seed, a wiper member supported in close proximity to said grid at one side thereof, means for producing relative movement of said grid and wiper member whereby one surface of the grid member will be traversed by the wiper member and a spring actuated baffle supported adjacent the opposite surface of the grid member.
- 30 19. In an apparatus of the character set forth, a ginning wall, a wiper pad engaging therewith, superposed spring plates having confronting fingers at the ends thereof engaging opposite sides of said pad to thereby grip the same therebetween, means securing said plates together to thereby clamp the pad, a support for said spring plates and means for producing relative movement between said ginning wall and said wiper pad.
- 35 20. In apparatus of the character set forth, a movable ginning wall having interstices therethrough, wipers disposed at one side of said wall and adapted to progress fibres of seed cotton through said interstices, yielding baffles normally stationary adjoining said wall and adapted to engage the seed on the wall opposite said wiper.
- 40 21. In apparatus of the character set forth, a ginning wall having interstices therethrough, wipers disposed at one side of said wall and adapted to progress fibres of seed cotton through said interstices, baffles normally stationary in relation to said wipers, and in opposition to the same at the opposite side of said wall and means for periodically moving said baffles away from said wall to relieve congestion of seed cotton on said wall.
- 45 22. In apparatus of the character set forth, a cylindrical grid composed of closely spaced rods, a circular frame supported in close relation to and conforming to said grid, a feed hopper supported by said frame and means for vibrating said frame.
- 50 23. In apparatus of the character set forth, a revolute cylindrical grid, an annular frame conforming to and supported in close relation to said grid and a screen having openings larger than ginned seed supported by said annular frame about said grid.
- 55 24. In apparatus of the character set forth, a movable ginning wall having interstices therethrough, wipers disposed at one side of said wall and adapted to progress fibres of seed cotton through said interstices and baffles normally stationary adjoining said wall opposing said wiper at the other side of said wall.
- 60 25. In apparatus of the character described, a ginning wall comprising small parallel rods with interstices between the same, wipers bearing on one side of said wall and adapted to progress fibres through said interstices, means for imparting relative motion to said wipers and ginning wall, transversely to said rods and means for automatically taking up the wear on the said wipers.
- 65 26. In apparatus of the character set forth, a ginning wall consisting of closely spaced relatively small rods forming a grid, wipers yieldingly engaging the surface of said grid, means for producing relative movement between said grid and wipers in a direction transverse to the rods and means for circulating a current of air through said grid and thence longitudinally of the rods thereof whereby to carry fibres through interstices between the rods and thence laterally away from the grid.
- 70 27. In apparatus of the character set forth, the combination of a ginning wall composed of non-rotatably supported closely spaced relatively small rounded rods forming a grid for supporting a body of seed cotton or the like material, means for inducing a current flow through said grid from the side where the seed cotton is supported to the

opposite side of the grid, a cotton fiber engaging member on the side of the grid opposite that at which the cotton is supported and means for imparting relative motion to 5 said fiber engaging member and the ginning wall to thereby cause fibers drawn through the interstices between the rounded rods by the current flow to be engaged and withdrawn by the fiber engaging member aforesaid.

28. In apparatus of the character set forth, the combination of a ginning wall composed of non-rotatably supported closely spaced relatively small rounded rods forming a 10 grid for supporting a body of seed cotton or the like material, means for inducing a current flow through said grid from the side where the seed cotton is supported to the opposite side of the grid, a cotton fiber engaging member on the side of the grid opposite that at which the cotton is supported, means for imparting relative motion to said fiber engaging member and the ginning wall to thereby cause fibers drawn through the interstices between the rounded rods by the current flow to be engaged and withdrawn by the fiber engaging member aforesaid and seed engaging means at that side of the ginning wall where the cotton is supported.

29. In apparatus of the character set forth, the combination of a ginning wall composed of non-rotatably supported closely spaced relatively small rounded rods forming a grid for supporting a body of seed cotton or the like material, means for inducing a current flow through said grid from the side where the seed cotton is supported to the opposite side of the grid, a cotton fiber engaging member on the side of the grid opposite that at which the cotton is supported, means for imparting relative motion to said fiber engaging member and the ginning wall to thereby cause fibers drawn through the interstices between the rounded rods by the current flow to be engaged and withdrawn by the fiber engaging member aforesaid and seed engaging means on that side of the ginning wall where the cotton is supported, said seed engaging means and ginning wall being relatively movable in respect to each other.

30. In apparatus of the character set forth, the combination of a ginning wall composed of non-rotatably supported closely spaced relatively small rounded rods forming a grid for supporting a body of seed cotton or the like material, means for inducing a current flow through said grid from the side where the seed cotton is supported to the opposite side of the grid, a cotton fiber engaging member on the side of the grid opposite that at which the cotton is supported, said member and the grid being in yielding engagement with each other and means for 55 imparting relative motion to said fiber en-

gaging member and the ginning wall to thereby cause fibers drawn through the interstices between the rounded rods by the current flow to be engaged and withdrawn by the fiber engaging member aforesaid. 70

31. In apparatus of the character described, a substantially circular ginning wall composed of relatively small substantially parallel closely spaced rounded rods adapted to support a body of seed cotton or like material on one side thereof, a wiper on the opposite side of said grid and means for producing relative rotation of said wiper 75 and the grid.

32. In apparatus of the character set forth, a grid member having passages for cotton fiber narrower than the cotton seed, a wiper member supported to co-operate with said grid member and comprising a strip of yielding material, means for moving the grid member with respect to the wiper member, whereby one surface of one of said members will be traversed by one surface of the other of said members, means for maintaining constant proximity of said members, whereby wear of the surfaces will be compensated for and means for creating a current flow of air through the grid member toward the wiper member. 85

33. In apparatus of the character set forth, a grid member having passages for cotton fiber narrower than the cotton seed, a wiper member supported to co-operate with said grid member and comprising a strip of yielding material, means for moving said wiper member with respect to the grid member, whereby one surface of one of said members will be traversed by one surface of the other of said members, means for maintaining constant proximity of said members, whereby wear of the surfaces will be compensated for and means for creating a current flow of air through the grid member toward the wiper member. 90

34. In apparatus of the character set forth, a ginning wall having interstices therethrough, means for supporting seed cotton on one side of said wall, wipers at the opposite side of said wall and adapted to progress fibers of the seed cotton through the interstices in the wall, a baffle disposed in close relation to the side of the wall where the seed cotton is supported and means for progressing the seed cotton past said baffle. 105

35. In apparatus of the character set forth, the combination of a ginning wall composed of closely spaced, relatively small, rounded rods forming a grid for supporting a body of seed cotton or like material on one side thereof, a wiper for engaging the opposite side of said grid, means for producing relative movement between said wiper and grid, means for inducing a flow of air through the grid from the supporting side to the opposite side thereof and a baffle at 125 110 115 120 125 130

the supporting side of the grid and disposed relatively close to the rounded rods forming the grid.

36. In apparatus of the character set forth, the combination of a grid composed of a plurality of relatively close initially spaced small round rods adapted to be contacted at one side by a body of seed cotton, or like material, a plurality of wipers disposed in spaced relation and comprising strips of material bearing on the rods at the opposite side of said grid and means for producing relative motion between the grid and wipers whereby the fibres will be drawn through the grid by the wipers and into the spaces provided between said wipers.

37. In a ginning machine, a grid composed of a plurality of cylindrical rods with air spaces between them and adapted to receive a body of seed cotton on the outside of said grid, a wiper member disposed inside of said grid having a working surface contacting with the interior wall of said grid, means for rotating said wiper member within said grid, and means for causing the movement of air through said grid from the outside toward the inside so that the wiper member in conjunction with the grid and the air current draws the fibers through the spaces between the cylindrical rods.

38. In a ginning machine, a grid member composed of cylindrical members with spaces between them to allow the passage of air and fiber, a wiper member inside of said grid member having a plurality of engaging pads adapted to engage the inner surface of said grid member and having air passages between said pads, means for rotating one of said members in relation to the other member to create a wiping action between the two, and means for causing the passage of a current of air through said grid toward the wiper members and through said passages between said pads.

39. In a ginning machine, a plurality of cylindrical rods arranged about a common axis with spaces between said rods for the passage of fibers, a wiper member rotatable with respect to said rods and having bearing surfaces frictionally engaging said rods to pull the fibers through the spaces between said rods, and means for causing passage of an air current between said rods toward said wiper member.

40. Apparatus for expelling extraneous substances from fibre, including means having a passage for fibre, a screen comprising a wall of said passage, baffle fingers supported in said passage and having unsupported free ends, means for progressing the fibre against and past said baffles and along said passage, and means for vibrating said screen.

41. Apparatus for expelling extraneous substances from fibre, including a passage for the fibre, a screen comprising a wall of said passage, pivoted baffle fingers supported in the path of the fibre moving through said passage, means for progressing fibre through said passage, and means of vibrating said baffles.

42. Apparatus for expelling extraneous substances from fibre, including means having a passage for the fibre, a screen comprising a wall to said passage, means for progressing the fibre along said passage, means including baffles for agitating the fibre in said passage, and means for oscillating said screen.

43. In a machine of the character described, an enclosure having passage for fibre, a screen composing a portion of the wall thereof, baffle fingers supported across said passage, means for progressing fibre along said passage, and means for vibrating the said screen and baffles.

44. Apparatus of the character described, including a circular screen adapted to support a body of fibre and having a circular passage imminently adjacent thereto, movable baffles in said passage adjacent said screen, means for progressing fibre along said passage, and means for moving said baffles independently of the means for progressing the fibre.

45. Apparatus of the character described, including means providing a circular passage for a body of fibre, a circular screen comprising a wall to said passage, means for circulating a current flow of air through said passage, baffle fingers projected across said passage, means for progressing fibre along the same, and means for vibrating said screen.

46. In a cotton treating mechanism, a passage way for fibrous substances, a grid comprising a portion of the wall of said passage way, movable fingers serving as baffles supported with their free ends adjacent the gridded wall, means for progressing fibrous substances through said passage way, and means for vibrating said baffles.

47. Ginning apparatus comprising multiple parallel movable rods forming a wall with interstices between the rods, wipers in contact with the wall at one side thereof, means for circulating air through said interstices toward said wipers, and means including pivotally movable fingers for agitating the seed cotton on the opposite side of said wall.

48. Ginning apparatus comprising a plurality of narrow throat entrances for fibre formed by a plurality of cylindrical rods, wipers in contact with the rods, means for circulating air through said throats toward said wipers, means including movable fingers for agitating the seed cotton on the side of

the rods opposite the wipers, and means for imparting relative motion between the rods and wipers.

49. Ginning apparatus comprising a movable ginning wall having interstices through the same narrower than the cotton seed, means for imparting motion to said wall, means for supporting a body of seed cotton on one side of said wall, wipers in contact with the opposite side thereof and forming therewith a bite for the fibre, and an independently movable member having confronting fingers extending toward and close to the said bite and adapted to move the seed in a direction corresponding approximately to the direction of the said elongated interstices.

50. Ginning apparatus comprising a plurality of wiper members with space between the several members serving as flues for air and lint cotton to pass through, a plurality of bar members supported in contact with the wiper members, means for supporting the several wiper members in yielding contact with the bar members, a common axis for the bar-supporting member and the wiper-supporting member, means for imparting relative motion between said members, a stripper provided with a plurality of confronting teeth adapted to engage the seed of the cotton while the fibre is drawing into the bite between a wiper and a bar member and adapted to pull on the seed in a direction the reverse of the pull on the fibre by the bar and wiper members.

51. Ginning apparatus comprising multiple parallel wiper members spaced apart multiple parallel round rods spaced apart to form interstices therebetween narrower than the seed of cotton, said rods forming a wall in contact with the wiper members, means for imparting relative motion between the wipers and the wall, means for circulating air through the interstices in the wall into and through the spaces between the wiper members, and means for agitating the seed cotton on the side of the wall opposite the side where the wiper members are located.

52. Ginning apparatus comprising multiple parallel revolvable rods forming a ginning-wall with interstices between the rods, wipers in contact with the wall at one side thereof and adapted to traverse the wall transversely of the rods, a movable stripper member with confronting teeth adapted to engage the seed of the cotton on the side of the wall opposite the wipers, and means for oscillating said stripper member.

53. Ginning apparatus comprising a movable ginning wall with interstices through the same, means for supporting a body of seed cotton at one side of said wall, wipers in contact with the opposite side of said wall and forming therewith a bite for the fibre,

an independently movable member having confronting finger portions extending toward and close to the said bite, and means for vibrating said member.

54. Ginning apparatus comprising a ginning wall with interstices through the same, means for supporting a body of seed cotton at one side of said wall, wipers disposed on the opposite side of said wall and adapted to progress fibres of seed cotton through said interstices, means for imparting relative motion between the wall and wipers, and means bearing on the seed to impart to them a lateral motion in relation to said wall.

55. Ginning apparatus comprising a plurality of wiper members with space between the several members serving as flues for air and lint cotton to enter and pass through, a plurality of rod members supported in contact with the wiper members, means for imparting relative wiping motion between the wiper and rod members whereby the former will wipe continuously in one direction transversely of the rod members, a pivotally mounted toothed stripper adapted to engage the seed of the cotton fibre entering between the wiper and rod members, and means for oscillating said stripper on its pivotal axis.

56. Ginning apparatus including a plurality of narrow throat entrances for fibre and formed by a plurality of bars comprising a rotatable cylindrical ginning wall, a discharge flue, wipers spaced apart and in contact with said wall, means for rotating said wall relatively to the wipers, automatic take-up means for compensating the wear on the wipers and the wall, channels between the wipers connecting the said throats and the said flue, and means for circulating an air current through the throats into the channels and thence into the discharge flue.

57. Ginning apparatus including a throat formed by two parallel rods spaced apart a distance less than the width of a cotton seed, drawing members for the fibre adapted to contact with one of the rods and having space between the drawing members sufficient to permit a mass of lint cotton to pass through, means for applying relative motion between the rods and drawing members whereby the fibres of seed cotton are drawn first through the throat and then into the spaces between the drawing members, and means acting on the seed to draw the seed away from said throat.

58. Ginning apparatus comprising a plurality of wiper members providing a surface of a nature to which the fibres of seed cotton will naturally attach themselves, two small round rods spaced apart sufficiently to admit the fibres between, a throat formed by the wide angle of the rounded surfaces

of the rods which will admit the ready passage of air and fibre but will resist the entrance of the seed, means for circulating air through said throat towards the wiper members.

5 63. In a cotton gin, the combination with 70 a narrow throat opening, formed by a round bar and a bar parallel thereto, of a wiper member adapted to form a contact with said round bar immediately adjacent said throat, means for maintaining relative motion between said round bar and wiper 75 whereby the two are intermittently brought into contact and the surface of the one is wiped by the surface of the other, and means for creating a current flow of air through 80 said throat and toward said point of contact between the round bar and wiper.

59. Ginning apparatus comprising a plurality of wiper members spaced apart to provide a passage between, and through 15 which air and cotton lint will pass freely and continuously in one direction, the wipers comprising strips of material of a nature such as cotton fibres will cling to, a small round rod in contact with said material, a 20 second rod spaced apart from and parallel to the first rod forming a throat between the rods too narrow for the cotton seed to pass through, means for circulating a current flow of air through said throat toward the 25 wipers, and means for rotating said rods relatively to the wiper members whereby the said wipers will traverse the rods transversely and draw the lint cotton through said throat.

30 60. Ginning apparatus comprising a plurality of narrow throat entrances for fibre formed by a plurality of cylindrical bars comprising a ginning wall, a discharge flue, wipers spaced apart and in contact with the 35 said wall, channels between the wipers connecting said throats and said discharge flue, and means for producing a current flow of air through said throats into said channels and thence into said discharge flue.

40 61. Ginning apparatus including a plurality of narrow throat entrances for fibre formed by parallel bars composing a cylindrical ginning wall, a discharge flue, wipers spaced apart and in contact with the wall, 45 channels between the wipers connecting the throats and the discharge flue, and means for circulating a current of air through said throats into said channels and thence into said discharge flue whereby the mass of fibre 50 entering said throats drifts continuously through and out of said channels into said flue.

62. Cotton ginning mechanism comprising a multiplicity of cylindrical rods supported 55 in parallel relation with space between adjacent rods which admits fibre of seed cotton to pass between the rods but too narrow to admit the seed, wiper members supported in contact with the rods and adapted to wipe 60 transversely across the rods continuously, space between the several wipers sufficient to admit a bulk of lint cotton detached from the seed, and means for imparting relative motion between said rods and wipers, whereby the fibres are drawn first between the

rods, then into and through the bite between the rods and wipers, and thence into the space between and contiguous to the several wipers.

63. In a cotton gin, the combination with 70 a narrow throat opening, formed by a round bar and a bar parallel thereto, of a wiper member adapted to form a contact with said round bar immediately adjacent said throat, means for maintaining relative motion between said round bar and wiper 75 whereby the two are intermittently brought into contact and the surface of the one is wiped by the surface of the other, and means for creating a current flow of air through 80 said throat and toward said point of contact between the round bar and wiper.

64. Cotton ginning mechanism comprising a multiplicity of cylindrical parallel rods supported with space between adjacent 85 rods which admits fibre of seed cotton to enter and pass through but too narrow to admit the seed, wiper members supported in contact with the rods and adapted to wipe transversely across the rods, space between 90 the several wipers sufficient to admit the bulk of lint cotton detached from the seed, and means for revolving the said rods whereby the fibres are drawn first between the rods then into and through the bite between the 95 rods and wipers and thence into the space between and contiguous to the several wipers.

65. Ginning mechanism including a cylindrical ginning wall comprising rods with 100 narrow spaces between, a member conforming to the cylindrical wall and provided with a series of prominences in contact with the cylinder, spaces between the prominences constituting conduits and in like series corresponding to and adjoining the prominences, and means for imparting relative 105 rotary motion to the cylinder and the said conforming member.

66. Ginning mechanism including a cylindrical ginning member comprising a grid, a member conforming to the cylindrical grid and provided with a series of prominences composed of strips of yielding material contacting with the grid member, spaces between the prominences comprising conduits, means for circulating air currents through the grid member toward the prominences in contact therewith and outwardly of the mechanism through said conduits, and means 115 of imparting relative rotary motion between the grid member and the conforming member.

67. Ginning mechanism comprising parallel and closely spaced bars constituting 125 a grid, wiper members relatively widely spaced and in contact with the grid, the spaces between the wiper members severally constituting flues, means for admitting air currents into said flues at the ends thereof, 130

and means for imparting relative motion between the grid member and the wiper members whereby fibres are drawn first through the grid member by the wiper members and thence through said flues by the air currents.

68. Cotton treating mechanism including a passage for fibre, a plurality of movable fingers projecting into said passage, a support for said fingers having a limited pivotal movement, means for rotating said support from its normal initial position in one direction and means for reversing the pivotal motion of said support and thereby 10 store the same to normal position.

69. Cotton treating mechanism including a passage for fibre, a plurality of movable fingers projecting into said passage, a support for said fingers having a limited pivotal movement, means tending to rotate said support from its normal initial position in one direction and a spring for restoring the same to its initial position.

70. Cotton treating mechanism including 25 means having a passage for fibre, a plurality of movable fingers projecting into said passage, a support for said fingers having a limited pivotal movement, means tending to rotate said support from its initial normal 30 position in one direction, means for restoring the same to its initial position and a screen adjacent said fingers.

71. Cotton treating mechanism including 35 means having a passage for fibre, a plurality of movable fingers projected into said passage, a support for said fingers having a limited pivotal movement, means tending to rotate said support from its initial normal 40 position in one direction, means for restoring the same to its initial position, a screen adjacent said fingers, and means for generating said current.

72. Ginning apparatus comprising a cylindrical ginning member composed of a multiplicity of small rods, smaller in diameter 45 than the normal length of cotton fiber and with spaces between said rods smaller than

the usual cotton seed so that fibers attached to a seed may pass through a plurality of spaces and means at one side of said member for engaging the fiber firmly and means on the opposite side of said member for engaging the seed whereby the seed and fiber may be pulled apart when said previously mentioned devices are moved with 50 relation to each other, and means for creating such relative motion.

73. Apparatus for cleaning cotton including two cylindrical walls, one within the other and the one inclosed by the other, the latter comprising a screen, a passage for fibrous substances separating the said walls, baffle fingers each supported at one end to extend into said passage to engage the fiber therein, each baffle finger having at its unsupported end an angular face whereby the material in the passage is moved longitudinally of the cylindrical walls when relative motion of the walls and the baffle fingers is set up and means for imparting said 60 relative motion.

74. Apparatus of the character described comprising a cylindrical screen forming one wall of a chamber for receiving and treating fiber, movable members in said chamber 75 having deflecting tips extending angularly and means for moving fiber around said chamber, said angular tips serving to laterally deflect the fiber from one side of said chamber to the other as it passes around said 80 screen.

75. Apparatus of the character described comprising a cylindrical screen forming one wall of a chamber for receiving and treating fiber and means for moving fiber around 85 said chamber within said screen and laterally thereof, said means including a plurality of movable baffle fingers having tips extending angularly therefrom at an inclination to the axis of said screen for moving the fiber laterally from one end of the cylinder toward the other as it travels around in said chamber.

WILLIAM D. McCOY.
